US0D1103097S

(12) **United States Design Patent** (10) **Patent No.:** **US D1,103,097 S**
(45) **Date of Patent:** **** Nov. 25, 2025**

(54) **WIRELESS CHARGER**

(71) Applicant: **Xiaohui Zeng**, Guangdong (CN)

(72) Inventor: **Xiaohui Zeng**, Guangdong (CN)

(**) Term: **15 Years**

(21) Appl. No.: **29/985,019**

(22) Filed: **Jan. 15, 2025**

(30) **Foreign Application Priority Data**

Jul. 26, 2024 (CN) 202430471319.7

(51) **LOC (15) Cl.** **13-02**

(52) **U.S. Cl.**

USPC **D13/108**

(57) **CLAIM**

The ornamental design for a wireless charger, as shown and described.

DESCRIPTION

FIG. 1 is a front, top and right side perspective view of a wireless charger, showing my new design;

FIG. 2 is a back, top and left side perspective view thereof;

FIG. 3 is a front elevational view thereof;

FIG. 4 is a back elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front, top and right side perspective view of the wireless charger, with the cover closed and the platform in a retracted state.

The broken lines shown in the drawings depict portions of the wireless charger that form no part of the claimed design.

1 Claim, 9 Drawing Sheets
